UNITED STATES PATENT OFFICE

SAMUEL BRAND, OF DAYTON, OHIO, ASSIGNEE TO THE NATIONAL CASH REGISTER COMPANY, OF DAYTON, OHIO, A CORPORATION OF MARYLAND

CASH REGISTER

Application filed June 3, 1927. Serial No. 196,325.

This invention relates to improvements in cash registers and more particularly to the totalizer control mechanism of the type shown and described in Letters Patent of the United States No. 1,619,796 issued to B. M. Shipley on March 1, 1927.

The object of this invention is to provide an automatic means for restoring the total control lever to its "add" position after the total of an itemized transaction has been printed.

With these and incidental objects in view, the invention consists of certain novel features of construction and combinations of parts, the essential elements of which are set forth in appended claims and a preferred form or embodiment of which is hereinafter described with reference to the drawings which accompany and form part of this specification.

20 Of said drawings:

Fig. 1 is a side elevation of the total control lever, together with the mechanism for restoring it to its "add" position.

Fig. 2 is a detail view of a part of the mechanism adjusted by the total control lever.

Fig. 3 is an enlarged detail view of a part of the mechanism for restoring the total control lever to its "add" position.

Fig. 4 is an edge view of the mechanism shown in Fig. 3.

Fig. 5 is a detail view of the mechanism for restoring the control lever to its "add" position, and shows the mechanism in the position to which it is moved near the end of the first cycle of a total-taking operation.

Fig. 6 is a detail view of the mechanism shown in Fig. 5, and shows the position to which the mechanism is moved near the end of the second cycle of a total-taking operation.

Fig. 7 is a detail view of the driving mechanism for the machine and shows the mechanism for controlling the machine so that it will receive two cycles of operation during total-taking operations.

Fig. 8 is a detail view in cross section, of the mechanism shown in Fig. 4.

General description

50 This invention is more particularly

adapted for use in itemized receipt printing machines of the type shown and described in the two co-pending applications for Letters Patent of the United States of B. M. Shipley, Serial Nos. 608,281 filed December 21, 1922, 55 and 687,305 filed January 19, 1924.

In machines of the type described in the above mentioned applications, each item of a transaction, or sale, is entered separately in the machine and then a total of all the items 60 for each transaction is printed. When the items are entered the total control lever is in its "add" position and before the total of the transaction is printed the total lever is adjusted to its first position below its "add" 65 position. This movement is effected manually before the machine is operated. After the total is printed and before another transaction, or sale, can be entered, it is necessary, in the machine disclosed in the above men- 70 tioned applications, to manually return the lever to its "add" position. By means of the present invention the total control lever is automatically returned to the "add" position at the end of every itemized transaction by 75 the machine, thus eliminating the necessity of manually returning the total lever.

In machines of this type, three lines of totalizers are usually provided and when it is desired to take either a total or sub-total 80 from a totalizer it is necessary to move the total lever to one of a plurality of positions for selecting one of the lines of totalizers. When the total lever is moved to any one of its plurality of positions, other than the one 85 for taking the total of an itemized transaction, the lever will not be automatically returned to its "add" position.

The method of controlling the machine by means of the total lever for total-taking operations and the various other functions of the total lever is not shown or described herein. For a detailed disclosure of these controls and functions reference may be had to the above mentioned patent. 95

Detailed description

The machine is provided with a total control lever 30 (Fig. 1) which is pivoted on a sleeve 31 mounted on a stud 32 in a well 100

known manner, as shown and described in the above mentioned patent. This lever 30 is provided for controlling the machine for item entering and for total-taking operations.

5 The full lines indicate the position of the lever when in its "add" position. The dot and dash lines indicate the position of the lever when it is moved to its first position below the "add" position for total-taking operations, which position is the one to which it is adjusted when printing a total of an itemized transaction.

10 The machine is provided with a main cam shaft 33 which receives one rotation in the direction of the arrow (Fig. 1) during each item entering operation and two rotations during every total-taking operation.

15 The cam shaft 33 may be rotated either by means of a motor, as described in the above mentioned patent, or by means of a crank (not shown) which is adapted to be clutched to a pinion 34 (Fig. 7) mounted to rotate on a hollow stud 35. The pinion 34 meshes with a gear 36 mounted on a stud 37. The gear 36 20 meshes with a gear 38 secured to the main cam shaft 33. Two rotations of the pinion 34 will give the gear 38 and shaft 33 one complete rotation. During total-taking operations the gear 38 is given two complete rotations. The reason for giving the shaft 33 two complete rotations during total-taking operations is well known in the art and is described in the above mentioned patent. Since 25 this forms no part of the present invention, no further description thereof is thought necessary.

30 The total lever 30 is provided with a rearwardly projecting lug 45 adapted to be moved into the path of one of two rollers 46 (Figs. 1 and 4), when the total lever is moved to its first position below its add position. The rollers 46 are mounted within an annular groove 44 of a collar 47. The collar 47 is rotated during total-taking operations for 35 causing one of the rollers 46 to engage the lug 45 for restoring the total lever to its add position.

40 The collar 47 is rotated by mechanism actuated by an arm 48 (Figs. 1, 5 and 6), having a roller 49 held in contact with a cam 50 on the main cam shaft 33 by a spring 43. Mounted on the rear end of the arm 48 is a stud 51 which is adapted to be engaged by a downwardly extending hook 52, pivoted on 45 an arm 53 secured to a short shaft 54. Also secured to the shaft 54 is a segment 55 which meshes with a partial gear 56 loosely mounted on a shaft 57, upon which the collar 47 is also mounted. (See also Fig. 4).

50 During the latter part of the first cycle of a total-taking operation the hook 52 is rocked to the left (Fig. 1) into the path of the stud 51. A guide 58 is secured to the arm 48 and also supports the stud 51. The guide 58 and 55 the rear end of the arm 48 act as a means for

guiding the hook 52 into proper position to be engaged by the stud 51. When the arm 48 is lowered by the cam 50 during the latter part of the operation of the machine, the hook 52 is lowered and by its contact with the hook 52 the segment 55 is rocked and it in turn rotates the partial gear 56 in a clockwise direction from the position shown in Fig. 1 to that shown in Fig. 6. During this clockwise movement of the partial gear 56, the collar 47 is held against rotation by a latch 59 (see also Fig. 3) which engages a notch 60 in one of the flanges of the member 47. The gear 56 is permitted to rotate independently of the collar 47 due to a clutch connection (Fig. 4) which is provided with a cam edge 61 on each of the clutch prongs. As the gear 56 rotates, the cam edges 61 will cause the gear 56 to be shifted toward the left (Fig. 4) against the tension of a spring 62 until said gear is disconnected from the collar 47. The right hand end of the spring 62 rests in a groove 63 (Fig. 3) in the gear 56, and the left hand end of the spring bears against a washer 64 (see also Fig. 8).

55 The downward movement of the hook 52 will drive the gear 56 through one-half rotation in a clockwise direction. At the end of this one-half rotation, the spring 62 will cause the gear 56 to be shifted toward the right (Fig. 4) to reengage the clutch prongs with the clutch slots of the collar 47.

60 The downward movement of the hook 52 will also stretch a strong spring 75 attached to the upper end of the arm 53. The spring 75 normally holds the arm 53 against a stud 76 (Fig. 5) carried by the side frame 77 of the machine. Just as the machine comes to rest and the total lever is free to be moved back to its add position, in a manner to be 65 hereinafter described, the spring 75 rotates the segment 55 in a clockwise direction, thereby rotating the gear 56 and collar 47 in a counter-clockwise direction. During the counter-clockwise movement of the collar the roller 46 engages the lug 45 and restores the 70 total lever 30 to its add position.

75 Before the collar 47 can be rotated in a clockwise direction, as just described, it is necessary to disengage the latch 59 from the notch 60. Mounted on the segment 55 is a stud 80 (Fig. 3), which near the end of the counter-clockwise movement of the segment 55, engages the arm 81 of the latch 59 thereby rotating the latch on its pivot 82 80 against the tension of a spring 83.

85 The arm 81 of the latch 59 is provided with a surface 84 long enough to maintain the latch out of the notch 60 until the periphery of the collar 47 passes beneath the nose of the latch 59. Just as the collar 47 completes its one-half rotation, the latch 59 will be engaged with the diametrically opposite notch 60 in the flange of the collar 47, thereby preventing further rotation thereof.

Overthrow of the collar 47 is prevented by a shoulder 85 on the latch 59, which is engaged by the right hand edge of the notch 60.

5 During the first cycle of a total-taking operation, the hook 52 is held in a position in which it is prevented from engaging the stud 51 by means of a link 90 slidably mounted on studs 91 and 92. The stud 91 is mounted 10 on a side frame of the machine, and the stud 92 is carried by an arm 93 pivoted on a stud 94. The right hand end (Fig. 1) of the link 90 is provided with a notch 89 embracing a stud 95 on the hook 52. When the total 15 control lever 30 is moved into any of its total-taking positions, the hook 52 is given a slight movement toward the left, but this movement is not enough to engage it with the stud 51. This initial movement is given the hook 52 20 upon the manual movement of the total lever, by means of a cam slot 96 (Fig. 2) into which a stud on an arm 97 projects. The arm 97 is pivoted on a stud 98 carried by the side frame of the machine and is adapted to rock an arm 25 99 by means of a flexible connection in the form of a spring 100. The arm 99 is provided with a cam slot 101 which is engaged by a stud on an arm 102 secured to a shaft 103. Also secured to the shaft 103 (Fig. 1) 30 is an arm 104, connected to the arm 93 by means of a link 105. The lower end of the arm 93 has pivoted thereto one end of a pitman 106 (see also Fig. 7) to be presently described. The link 90 is provided with a 35 slot 108 the upper end of which engages the stud 92, and is held in engagement therewith by means of a spring 109 stretched between the stud 92 and a stud 110 on the link 90.

Movement of the total control lever 30 out 40 of its "add" position will cause the shaft 103 to be rocked in a clockwise direction (Fig. 2) by means of arms 97, 99 and 102 rocking the arm 104 in a clockwise direction and by means 45 of a link 105 rocking the arm 93. This movement of the arm 93 assisted by the spring 109, moves the link 90 toward the left (Fig. 1).

Near the end of the first cycle of operation the link 90 is given an additional movement toward the left (Fig. 1) by a cam 115 50 (Fig. 7) mounted to rotate on the stud 37 in a recess in the gear 36. The cam 115 is held against rotation during adding operations of the machine by means of a slideable coupler 116 in a usual and well known manner. When the arm 93 is rocked as above 55 described, the pitman 106 will be moved toward the left (Fig. 7) to slide the coupler 116 to couple the cam 115 with the gear 36 to cause rotation of the cam 115. The pitman 106 is provided with two studs 118 60 between which an upwardly extending flange 119 of the coupler 116 projects. As the pitman 106 is moved toward the left (Fig. 7) the studs 118 will slide the coupler 116 there- 65 with into engagement with a notch 120 in

the gear 36 thus coupling the cam 115 to the gear 36.

The pitman 106 is provided with an anti-friction roller 125 (Fig. 7) which projects into a notch in the cam 115 when the total control lever is in the add position, but which is moved into a cam race 126 of the cam 115 when the total control lever is moved out of its add position as just described. 70

The cam race 126 is so timed that near the 75 end of the first rotation of the shaft 33, the pitman 106 will be rocked still farther toward the left (Fig. 7) thereby giving the arm 93 an additional clockwise movement.

Just before the cam race 126 moves the 80 pitman 106 toward the left, the cam 50 will move the arm 48 to its lower position as shown in Fig. 5. After the arm 48 has thus been lowered the cam race 126 will cause the arm 93 to be rocked in a clockwise direction 85 as just described which movement will be enough to permit the link 90 to be moved to the left (Fig. 5) to cause the hook 52 to be moved into the path of the stud 51. At the end of the first rotation of the shaft 90 33 the strong spring 43 raises the arm 48. As the arm 48 is raised the stud 51 will cam the hook 52 and link 90 toward the right (Fig. 5) against the tension of the spring 109. After the stud 51 has passed 95 the hook 52, the spring 109 moves the link 90 and hook 52, toward the left (Fig. 5) thereby moving the hook beneath the stud 51. Near the end of the second rotation of the shaft 33 the arm 48 is again lowered, 100 as shown in Fig. 6, thereby lowering the hook 52 to rotate the gear 56 in a clockwise direction, as before described. At the very end of the second cycle of operation 105 of the shaft 33 the spring 43 will again raise the arm 48 thereby disengaging the stud 51 from the hook 52.

The total control lever 30 cannot be returned to its add position until the machine 110 has reached its home position. For this reason the hook 52 cannot follow the arm 48 to its normal position when said arm is raised by the spring 43 near the end of the second cycle of operation of the machine. However, the hook can follow for a short 115 distance, until the roller 46 engages the lug 45, whereupon it will be prevented from moving, because at this time the total lever cannot be moved. When the cam 115 (Fig. 7), reaches its home position and the roller 120 125 is in position to again engage the notch, as shown in Fig. 7, the pitman 106 will be free to be moved toward the right thereby permitting the counter-clockwise rotation of the arm 93. This will permit the spring 125 75 to complete the counter-clockwise rotation of the collar 47 thereby causing the lever 30 to be returned to its "add" position. However, this movement will not take place until the shaft 103 is free to be moved by the 130

cam slot 96 in the total lever. Thus when the roller 125 moves into the notch in the cam 115, the shaft 103 will be free to move and therefore the cam slot 96 can rock the shaft 103 thereby permitting the total control lever 30 to be returned to its "add" position.

Movement of the arm 93 when the total lever is returned to its "add" position will 10 cause the link 90 to be moved toward the right (Fig. 6). For this reason the link 90 is cut away to the edge 135 (Fig. 6) so that even though the link 90 shall have been moved toward the right from the position shown in Fig. 6, the stud 95 will be cammed into the notch 89 by means of the spring 75.

When the control lever 30 is moved into any one of the total-taking positions except 20 the first position below adding position, the lug 45 will not be in the path of one of the rollers 46, and therefore the control lever will not be returned to its "add" position at the end of the operation. Thus it is seen 25 that the only position from which the total control lever may be automatically returned, is the first position below add position, which first position is the one for controlling the totalizer for printing the total of an itemized 30 transaction or sale.

Operation

A brief description of the operation of the mechanism will now be given. During 35 adding operations the total control lever is left in its "add" position in which position the lug 45 is out of the path of the rollers 46 for returning the lever and therefore the lever will not be affected during adding operations. The means for rotating the 40 collar 47 is normally held in a position in which it will not become effective to rotate the collar, and therefore during adding operations the mechanism does not function.

45 When the total lever is moved to the first position below add the hook 52 is moved a short distance, but not far enough to become engaged with the stud 51. After the arm 48 has been lowered the hook 52 is moved toward 50 the left far enough to be moved into the path of the stud 51. Upon upward movement of the arm 48 the hook 52 snaps over the stud 51 and upon subsequent downward movement of the arm 48 the hook 52 is lowered to rotate 55 the gear 56 in a clockwise direction and stretch the total lever restoring spring 75. The gear 56 is rotated independently of the collar 47 during this movement, due to the latch 59 and the clutch connector, but when 60 the gear 56 receives one-half rotation, the latch 59 is disengaged from the collar 47. Near the end of the second cycle of operation the arm 48 is raised and as the machine reaches its home position the hook 52 is released thereby permitting one of the rollers 65

46 to return the total lever to its add position.

If the lever is moved to any other position except the first position out of "add" the mechanism for returning the total lever will be operated idly because the lug 45 will not be in the path of the rollers 46. Thus the total lever will only be returned from its first position out of add.

70 While the forms of mechanisms herein shown and described are admirably adapted to fulfill the objects primarily stated, it is to be understood that it is not intended to confine the invention to the forms of embodiment herein disclosed, for it is susceptible of embodiment in various forms all coming within 75 the scope of the claims which follow.

What is claimed is:

1. In a machine of the class described, the combination of a total control lever having an add position and a total-taking position, 80 said lever being adapted to be set manually into its total-taking position, a rotatable member adapted to cooperate with said lever for restoring it from its total-taking position to its add position, a normally inactive spring 85 device for rotating said member, means operable during all operations; and means operating only during total-taking operations to connect said device to said operable means and to release said device from said operable 90 means.

2. In a machine of the class described, the combination of a total control lever having an add position and a total-taking position, 100 said lever being adapted to be set manually into its total-taking position, a rotatable member adapted to cooperate with said lever for restoring it from its total-taking position to its add position, a normally inactive spring 105 device for rotating said member, a normally disconnected operating means for rendering the spring active during total-taking operations, and mechanism operable by the lever when the lever is moved to its total-taking position to connect the spring with the operating 110 means.

3. In a machine of the class described, the combination of a total control lever having an add position and a total-taking position, 115 said lever being adapted to be set manually into its total-taking position, a rotatable member, a means carried by said rotatable member adapted to cooperate with the lever for restoring the lever to its add position at the end of a total-taking operation, a spring actuated device for rotating said member, an arm operable during every operation of the machine, and means for connecting said device with the arm during total-taking operations for causing said device to become effective.

4. In a machine of the class described, the combination of a total control lever having an add position and a total-taking position, 120 said lever being adapted to be set manually 125

70

into its total-taking position, a member rotatable in one direction only, means carried by said rotatable member adapted to contact the lever for restoring the lever to its add position, a reciprocating device for rotating said member, connections between the reciprocating device and said member effective to rotate the member in one direction only, and means for operating the reciprocating device during total-taking operations.

5. In a machine of the class described, the combination of a total control lever having an add position and a total-taking position, said lever being adapted to be set manually into its total-taking position, a rotatable member, means carried by said rotatable member adapted to cooperate with the lever for restoring the lever to its add position, a reciprocating device for rotating said member when the device is moving in one direction, an arm adapted to be operated during every operation of the machine, means for engaging the reciprocating device with the arm during total-taking operations, said arm adapted to move the device in one direction, and a spring for returning the device to its normal position for rotating the rotatable member after the end of a total-taking operation.

6. In a machine of the class described, the combination of a total control lever having an add position and a total-taking position, said member being adapted to be set manually into its total-taking position, a rotatable member, means carried by said rotatable member adapted to cooperate with the lever for restoring the lever to its add position, a reciprocating device for rotating said member when the device is moving in one direction, an arm adapted to be operated during every operation of the machine, means for engaging the reciprocating device with the arm during total-taking operations, said arm adapted to move the device in one direction, a latch for holding the rotatable member against rotation when said arm operates said device, and a shoulder on the latch for stopping the rotatable member after the member has restored the lever for preventing overthrow of said member.

7. In a machine of the class described, the combination of a total control lever adapted to be adjusted manually out of its normal position, a rotatable member for restoring the lever to its normal position, a reciprocable device for rotating said member, a latch for holding the rotatable member against movement while the device is moving in one direction, means actuated by said device for unlatching said latch, and a shoulder on said latch for preventing overthrow of the rotatable member.

8. In a machine of the class described, the combination of a total control lever having an add position and a plurality of total-taking positions, means for restoring said

lever to the add position, and a projection on said lever adapted to be moved into cooperative relation with said means when the lever is moved into one of said total-taking positions, whereby the means restores the 70 total lever to its add position at the end of the total-taking operation.

9. In a machine of the class described, the combination of a total control lever having an adding position and total-taking position, 75 said lever being adapted to be set manually into its total-taking position; a rotatable member; means carried by said member to cooperate with the total lever to restore said lever to its adding position; operating means to rotate said member; a member operable during every operation of the machine; a flexibly mounted device connected to said operating means, and normally disconnected from said operable member; and means connected to said device and operated under control of the total lever as it is manually moved to its total-taking position, to connect said device to said operable member.

10. In a machine of the class described, the combination of a total control lever having an adding position and a total-taking position, said lever being adapted to be set manually into its total-taking position; a rotatable member; means carried by said member to cooperate with the total lever to restore said lever to its adding position; operating means to rotate said member; a member operable during every operation of the machine; a projection on said operable member; a flexibly mounted device connected to said operating means, and normally disconnected from said operable member; means projecting from said flexibly mounted device; means embracing said projecting means to connect said flexible device with the projection on the operable member; and guiding means on the operable member to prevent displacement of the flexible device.

11. In a machine of the class described, the combination of a total control lever having an adding position and a total-taking position, said lever being adapted to be set manually into its total-taking position; a rotatable member; oscillating means connected to the rotatable member to cause the rotatable member to always rotate in one direction; a lug projecting from the total lever; means carried by the rotatable member to cooperate with the lug to restore the total lever to its adding position; a member operable during every operation of the machine; a flexibly mounted device connected to said oscillating means and normally disconnected from said operable member; and means operated under control of the total lever as it is manually moved into its total-taking position, to connect said flexible device to said operable member.

12. In a machine of the class described, the

combination of a total control lever having an adding position and a total-taking position, said lever being adapted to be set manually into its total-taking position; a rotatable member; oscillating means to operate the 5 rotatable member; means intermediate the oscillating means and the rotatable member to cause said member to rotate in one direction only; means carried by said rotatable member to cooperate with the total lever to restore said lever to its adding position; a member operable during every operation of the machine; a flexibly mounted device connected to said operating means and normally disconnected from said operable member; a 10 normally inactive spring connected to the flexible device; means connected to said flexible device, and operated under control of the total lever as it is manually moved into its total-taking position, to connect said flexible device to said operable member; and a cam 15 device to operate the last named means to disconnect the flexible device from the operable member.

13. In a machine of the class described, the 20 combination of a total control lever having an adding position and a total-taking position, said lever being adapted to be set manually into its total-taking position; a rotatable member; means carried by said member to cooperate with the total lever to restore 25 said lever to its adding position; operating means to rotate said member; a member operable during every operation of the machine; a normally ineffective spring actuated 30 device connected to said actuating means and normally disconnected from said operable member; reciprocating means operable upon one direction of its movement to connect said flexible device with said operable member, and operable upon the other direction of its 35 movement to disconnect said flexible device from the operable member.

In testimony whereof I affix my signature.

SAMUEL BRAND.
